COKING RETORT OVEN FOR LOW OR
MEDIUM TEMPERATURE COOKING

Wilhelm Fitz, Essen, Germany, assignor, by mesne assignments, to Koppers Company, a corporation of Delaware

Application February 17, 1934, Serial No. 711,658
In Germany February 18, 1933

1 Claim. (Cl. 202—139)

The invention relates to the medium or low temperature coking of fuels, such as mineral coal and the like, whilst extracting by-products from the gaseous and vaporous products produced 5 during the coking.

The expression medium temperature coking implies coking at temperatures of about 700° C. carried out as a rule in the known horizontal chamber ovens or similar ovens for the production of gas and coke. By such a medium temperature coking there is produced a coke containing a comparatively large quantity of volatile constituents and which is readily ignitable and capable of entering into reaction so that 10 this coke can also be burnt in the usual household stoves and in open fires. The burning of such a coke has the advantage that no smoke and soot are formed or if so only in very small quantities.

20 The so called low temperature coke is produced at still lower coking temperatures than medium temperature coke, preferably at temperatures of about 620 to 650° C. Its production is mostly effected in retorts of iron or other suitable 25 metallic materials. Low temperature coke also produces very little smoke and soot during burning.

In addition to coke there are also produced, during medium and low temperature coking of 30 fuels, by-products, particularly light and heavy hydrocarbons, whilst the amount of other substances, such as ammonia, is only very small. Amongst the hydrocarbons—in contrast to the by-products from the known high temperature 35 coking—is included a comparatively large quantity of acid compounds (phenols, cresols and the like). Especially in the case of low temperature coking these acid products considerably reduce the value of the tar produced from the distillation products of medium and low temperature 40 coking. Further the yield in benzol is lower in the case of medium and low temperature coking of fuels than in the case of high temperature coking.

45 By-products of similar composition have also already been observed when coking in the known continuously operated vertical chamber ovens, which are used to a large extent in gasworks and the like. In these coking ovens the coal to be 50 converted into coke is supplied continuously or at short intervals at the upper end into the coking chamber, whilst the coke which is formed is also withdrawn continuously from the lower end of the chamber. In the upper part of the coking 55 chamber the fuel is subjected for a period of

time, i. e. until it reaches the zone at a high temperature to relatively low temperatures so that the fuel is preferably subjected in its outer layers to a kind of distillation or a coking at low temperatures during which there are also 5 formed distillation products rich in acid constituents.

Large quantities of acid compounds are not desired in the by-products of coal distillation, mainly because they are soluble in water and 10 thus render the use of the tar impossible for road construction. Also the slight presence of valuable benzol, which always runs parallel with the increased presence of acid products, considerably 15 reduces the economy of the coking of coal. 15

The object of my present invention is to provide such improvements in the coking of fuels at low temperatures that by-products are formed which have substantially the same character and composition as the valuable by-products of the 20 known high temperature coking.

I have found that from the distillation products of medium or low temperature coking valuable by-products are obtained when the distillation products are subjected to a heat treatment at a 25 high temperature directly after they are formed, i. e. before they are condensed. By such a heat treatment particularly the acid hydrocarbons are 30 decomposed whilst forming low hydrocarbons, especially benzol and its homologues. 30

According to my present invention the gaseous and vaporous distillation products produced during the medium or low temperature distillation of fuel are subjected after escaping from the fuel mass to be coked or the charge of the coking chamber or retort, to a heat treatment at a 35 temperature higher than that corresponding with the temperature of production or the coking temperature and only after this, are conducted in to the usual plant serving for the extraction of the 40 by-products.

My invention may for example be carried out in the manner that the distillation products produced during the dry heating of the fuel, after leaving the distillation chamber, are conducted 45 into a separate heater in which they are subjected to the necessary heat treatment for cracking the hydrocarbons.

In order to avoid the provision of a separate heating device for carrying out my invention it 50 is further possible according to my invention to so construct the distillation device in which the fuel is coked that the chamber, in which the distillation gases collect, is heated to a higher temperature than the portion in which there is 55

located the fuel to be coked or distilled. In the case of horizontal chamber ovens for the production of gas and coke this idea is preferably developed in the manner that the heating passages provided in the usual manner in the walls of the coking chambers are also provided in that part of the chamber walls which forms the so called gas collecting chamber of the coking chamber. In this case it is also advantageous to make 10 the thickness of the walls between these heating passages and the gas collecting chamber less than the thickness of the walls between the part of the chamber receiving the fuel and heating passages adjacent thereto.

15 Finally in the case where the coking or distillation of the fuel is effected by means of a current of hot gases, which is brought into direct contact with the fuel, my present invention may be carried out in such a manner that the gaseous or vapourous products escaping from the fuel together with the heating gas are led to a device for heating these gas masses whereupon a portion of these gases is conducted continuously or periodically to the device for separating the by-products.

Further objects of my invention will appear from the following detailed description. In Fig. 1 is shown in vertical longitudinal section a suitable horizontal chamber oven battery suitable for 30 carrying out my invention. Fig. 2 shows a vertical section of a part of a horizontal chamber oven battery on the line II—II of Fig. 1. In the horizontal chamber oven battery shown in the drawing the coking chambers 1, which 35 serve to receive the fuel, for example, mineral coal, to be treated, are formed of walls 2, consisting of refractory masonry in which vertical heating passages 3, 4 are provided, these heating passages are connected at the top and bottom in 40 pairs by openings 5, 6. Gas and air are alternately supplied to the bottom of the heating passages 3 and then to the bottom of the heating passages 4. The waste gases formed by the combustion of the heating gas rise in the heating passage supplied at the bottom with gas and air and pass into the adjacent heating passage of each 45 pair of heating passages in which they then pass downwardly. At the bottom of the heating passage through which the waste gases pass 50 downwardly a portion of the waste gases then passes through the lower communicating opening 6 into the adjacent heating passage where this portion of the waste gases mixes with the heating gas and combustion air. In this manner 55 the combustion is delayed so that a comparatively long flame is formed which effects a very uniform heating of the chamber walls along the entire height thereof. This heating system is generally known under the name "circulating 60 current heating".

For pre-heating the combustion air and eventually also the heating gas, should weak gas such as generator gas or furnace gas be used for heating the oven, regenerators 7, 7a, 8, 8a, are 65 provided under the oven chambers. For pre-heating there are alternately used the media to be pre-heated which are supplied to the regenerators 7 and 7a located on one side of the battery and then to the regenerators 8, 8a located on the 70 other side of the oven battery. The regenerators are connected by passages 9 to the heating passages located above them. The heating passages located on the other side of the battery are connected to the regenerators by the horizontal 75 passages 10, 11. With each regenerator

is associated a horizontal passage 10 and 11 respectively. The horizontal passages 10, 11 of oppositely disposed regenerators cross one another at the middle of the oven battery, as indicated at 12, without any communication being formed 5 between these two horizontal passages 10, 11. Branch passages 12 lead from the horizontal passages to the separate heating passages. As will be seen from Fig. 1 of the drawing each of the regenerators 7 located on one side of the battery 10 communicates with the heating passage 3 of each pair of heating passages, whilst the regenerator 8 located on the other side of the battery communicates with the heating passage 4 of each regenerator pair. As will be seen in Fig. 1 each 15 regenerator is always connected to the heating passages 3 or 4 connected together in two adjacent heating walls.

The heating of the coke oven battery is such that for example gas and air is first supplied to 20 the regenerators 7. The media are pre-heated in the regenerators, provided as usual with refractory chequer work, pass into the heating passages 3 and there burn. The waste gases then 25 pass through the heating passages 4 and from here into the regenerators 8 and heat the refractory chequer work thereof.

The inlet opening 13 of each regenerator communicates with a so called knee piece 14. This knee piece 14 has a series of valves which can be actuated by an actuating lever 15. These valves control openings in the knee pieces which lead to the pipe leading to the waste gas passage 16 and to the pipe 18 to which the heating gas pipe 19 is connected. In addition the knee pieces, as usual, are provided with an outwardly opening air flap. The knee pieces are so constructed that the regenerator to which the knee piece is connected, can be connected selectively either to the waste gas passage 16 or to the heating gas 40 piece 19 or to the outer air.

When the coke oven battery is to be heated by rich gas, which does not require to be pre-heated, for example coal distillation gas, gas is conducted from the rich gas pipes 20, through 45 pipes 22, each controlled by a valve 21, into horizontal passages 23 which are located underneath the heating walls, in the oven masonry. These passages 23 either communicate with the heating passages 3 or the heating passages 4 50 of the heating walls so that according to requirements rich gas may be supplied either to the heating passages 3 or to the heating passages of each heating wall.

For charging coal into the coking chambers 55 charging openings 24 are provided in the roof thereof which can be closed by removable covers 25. Further there is provided in the roof of each coking chamber a gas outflow opening 26 to which there is connected the stand pipe 28 60 leading to the hydraulic main 27.

At the sides the coking chambers are cased by means of doors 29 which for the purpose of discharging the finished coke are removed from the door opening.

After coal has been charged into the coking chambers through the openings 24, the surface of the charge is levelled from the outside by means of a usual levelling rake. For introducing the levelling rake into the chamber openings 30 70 are provided on the doors 29 which are closed by flaps 31 after the levelling of the coal has been completed.

By reason of this levelling of the coal charge there is formed above the latter in the chamber 75

5 a free space, the so-called gas collecting space. Laterally adjacent this gas collecting space no heating passages are provided in the chamber wall in horizontal chamber coking ovens of usual construction as at too high a temperature of the gas collecting space the gas contained therein is decomposed.

10 In the coke oven according to the invention, however, the heating passages extend almost up to the roof of the coking chamber as is clearly shown in Fig. 2. Further the heating wall at the portion 33 thereof defining the gas collecting chamber is made thinner than the remaining parts of the wall. By these two provisions the 15 gas collecting space is heated to the higher temperature, advantageously in medium or low temperature coking, as compared with the actual coking space of the chamber. The gases passing through the gas collecting space are consequently 20 subsequently heated to a higher temperature than that which they possessed on production and within the coal charge, whereby the molecular distribution and modification of the hydrocarbons contained in the gases desired, according 25 to the invention, takes place.

30 The obtaining of definite temperatures inside the coking chamber naturally determines the use of predetermined thickness of wall. Preferably the thickness of the chamber wall at the parts defining the actual coking chamber is selected at about 130 to 150 millimetres, whilst at the gas collecting space it is only about 70 to 100 millimetres. This difference in the thickness of wall produces a temperature difference inside the 35 chamber between the upper and lower parts of the wall of about 150 to 200° C., when the temperature of the lower parts of the chamber wall is maintained at about 700° C. The gas collecting space under these conditions is heated to a 40 temperature of about 850 to 900° C. When using coking temperatures necessary for medium temperature coking for the production of a readily combustible fuel the oven is capable of introducing a reaction which is obtained in practice 45 also from the gases in the case of the usual high temperature coking so that the formation of by-products, which to a far reaching extent correspond with those of high temperature coking, is ensured.

50 Instead of reducing the thickness of the chamber wall at the upper end in stages, as shown in Fig. 2, it may be preferable under certain circumstances, to reduce the thickness of the chamber wall gradually towards the top.

55 It may also be mentioned that also the cross section of the gas collecting space must be suitably dimensioned in order to ensure a sufficient delay of the gases in the hot gas collecting space for the desired subsequent heating of the distillation gases. Finally in carrying out my invention it is also possible to treat in the coking chamber, together with the solid fuel, condensates which have been formed in another low or medium temperature coking, for the purpose of extracting valuable substances from these by-products. In this case the said condensates are

preferably mixed with the coal to be treated before charging this into the coking chamber or adding them thereto during the charging of the coal so that the condensates are uniformly distributed in the chamber charge. Such a cooperation of condensates from low or medium temperature coking arises, for example, when in a separate device, for example a rotary tube oven, semi or resinous coke is produced which is mixed with the coal to be treated for the purpose of 10 obtaining a dense or compact coke.

15 In addition to the conversion of the condensable hydrocarbons there is also obtained by the use of my present invention, an advantageous conversion of the hydrocarbons which are gaseous, i. e. low molecular at ordinary temperature, into hydrogen and carbon. It is thus possible also to produce by low or medium temperature coking, a gas with an average heating value which can be burnt in the usual gas firings without 20 modifying the burning devices.

25 I have described my present invention with reference to a specific example of construction but it is to be understood that my invention is not to be limited to this particular form of construction. My invention may be suitably modified within the scope of the following claim.

I claim:

30 A coking retort oven for low or medium temperature coking comprising a series of alternate horizontal coking chambers and heating walls therefor arranged side-by-side in a row, each of said coking chambers having a distillate gas off-take leading from the top of the chamber and a leveller door at one end thereof near the top of the chamber and being adapted for being charged with coal up to the level of the bottom of the leveller door opening so as to provide a gas off-flow free space-portion along the top of the coking chamber for off-flow of distillate from a 35 charge in the chamber over the top of the charge lengthwise of the coking chamber to the off-take therefor, each of said heating walls comprising vertical combustion flues having burners at their lower parts and off-takes for waste gases at their 40 upper parts, said vertical combustion flues extending upwardly above the level of the bottom of the leveller door opening and almost as high as the level of the tops of the adjacent coking 45 chambers, and substantially all of the portions of the heating walls between the upper parts of the flues and the portions of the tops of the adjacent chambers adapted for being the aforesaid gas off-flow free-space portion being of a thickness of substantially 70 to 100 millimetres as 50 compared with a thickness of substantially 130 to 150 millimetres in the lower portions of the heating walls between the flues and the adjacent coking chambers starting below so as to cause by such relative thinness a higher heating of the 55 gas off-flow free-space portions than the portions of the chambers below the same to crack distillation gas that may flow through such free-space 60 portions during flow thereof to the gas off-takes.

65
WILHELM FITZ.
